UNITED STATES PATENT OFFICE.

LYMAN S. POWELL, OF CHICAGO, ILLINOIS.

AUTOMATIC CONTROL FOR BOILER-FURNACES.

1,370,765.

Specification of Letters Patent.

Patented Mar. 8, 1921.

Application filed December 17, 1917. Serial No. 207,571.

To all whom it may concern:

Be it known that I, LYMAN S. POWELL, a citizen of the United States, and a resident of the city of Chicago, county of Cook, and 5 State of Illinois, have invented a certain new and useful Automatic Control for Boiler-Furnaces, of which the following is a specification.

My invention relates to automatic controls for boiler-furnaces, and has for its object the provision of means, operable by the water flowing to the boiler, for automatically controlling the draft passing through the furnace and cause more rapid combustion therein when the supply of water to the boiler is increased and vice versa.

The invention consists in the combinations and arrangements of parts hereinafter described and claimed.

20 The invention will be best understood by reference to the accompanying drawings forming a part of this specification, and in which,

Figure 1 is a side view, shown partially 25 in section, of a construction embodying my invention,

Fig. 2, a section taken on line 2—2 of

Fig. 1,

Fig. 3, a section taken on line 3—3, of 30 Fig. 1,

Fig. 4, a detail view illustrating a smoke stack damper and the connection therewith, and, Fig. 5, a side view of a boiler furnace equipped with the automatic control illustrated in Figs. 1, 2, 3 and 4.

The preferred form of construction, as 40 illustrated in the drawings, comprises a fitting 5 adapted to be inserted in the boiler feed pipe and provided centrally with a vertically arranged cylinder 6 open at one side and bottom 7 to the incoming passage 8 of fitting 5. The other side of cylinder 6 is provided with a vertical slot 9 permitting, when open, escape of water from cylinder 45 6 through the outlet passage 10 of the fitting 5. Cylinder 6 is provided with a removable lining 11 having a slot 12 registering with the slot 9 in said cylinder. A piston 13 operates in cylinder 6—11, a set screw 50 13' being provided in the bottom of fitting 5 to give free access to the incoming water to the bottom of said piston at all times. The piston 13 is provided with a piston rod 14 operating through an ordinary stuffing box 55 15 in the cylinder head 16, said cylinder head 16 being secured in position by means

of a number of stud bolts 17, whereby the angular position of said cylinder head may be readily adjusted on said cylinder. Two upstanding guide rods 18 and 18' are secured to cylinder head 16 and are connected at their upper ends by means of a yoke 19. A weight 20 is adjustably secured to piston rod 14 and a cross head 21 is also secured to said piston rod and given slidable bearings 65 21' on the guide rods 18 and 18'. Cross head 21 is provided at one side with a laterally extending arm 22 connected with the upper end of a flexible cable 23 which is secured to and wound upon a grooved pulley 24. Pulley 24 is rigidly fixed to a companion and larger pulley 25, both of said pulleys being loosely mounted on a shaft 26 in a bracket 27 adjustably mounted on guide rod 18' and secured in adjusted positions by means of set screws 28. A flexible cable 29 is secured to and wound upon pulley 25 in a direction opposite to the direction of winding of cable 23 on pulley 24, the upper end of cable 29 being secured to the 80 lower end of a weighted operating arm 30 operating damper 31 in smoke stack 32 of the boiler-furnace.

By this arrangement, water entering fitting 5 through the passage 8 will operate 85 upon the piston 13 to elevate the same, elevation of said piston operating through pulleys 24 and 25 and cables 23 and 29 to open damper 31 to cause greater draft through the boiler-furnace, as will be readily understood. Further increase of the supply of water passing through fitting 5 will elevate the piston 13 still farther, thus opening damper 31 still farther to increase the draft to correspond, thus causing more rapid combustion in the boiler-furnace and consequently the application of greater heat to the boiler to correspond with the increased supply of water passing thereto. Upon decrease of the supply of water passing 100 through fitting 5, the piston 13 descends to correspond effecting a corresponding adjustment of damper 31 to decrease the amount of heat supplied to the boiler. By inserting different linings 11 with slots 12 105 of different widths, the apparatus may be nicely adjusted to different boiler conditions. By adjusting cylinder head 16 on the fitting 5 and bracket 27 on the guide rod 18' the apparatus may be readily adjusted to 110 meet various conditions as to space and arrangements of parts.

Cross head 21 is also provided with a laterally extending arm 33 connected with the upper end of a piston rod 34 of an ordinary dash pot 35 mounted upon rod 18 by means of a bracket 36, said dash pot being an ordinary type of dash pot and arranged to check sudden downward movements of piston rod 14 but to permit of free upward movement thereof, thus tending to prevent too sudden changes in the draft of the boiler-furnace.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

25 1. The combination with a boiler-furnace smoke stack damper, of a fitting in the boiler feed pipe; a cylinder in said fitting in open communication with water flowing through said fitting, there being a slot in the wall of said cylinder; a piston in said cylinder; and an operative connection between said piston and said damper, substantially as described.

35 2. The combination with a boiler-furnace smoke stack damper, of a fitting in the boiler feed pipe; a cylinder in said fitting in open communication with water flowing through said fitting, there being a slot in the wall of said cylinder; a removable lining for said cylinder having a slot registering with said cylinder slot; a piston in said cylinder; and an operative connection between said piston and said damper, substantially as described.

45 3. The combination with a boiler-furnace smoke stack damper, of a fitting in the boiler feed pipe; a cylinder in said fitting in open communication with water flowing through said fitting, there being a slot in the wall of said cylinder; a piston in said cylinder; two rigidly connected pulleys; a flexible element wound upon one of said pulleys and operatively connected with said piston; and a flexible element oppositely wound on the other pulley and operatively connected with said damper, substantially as described.

60 4. The combination with a boiler-furnace smoke stack damper, of a fitting in the boiler feed pipe; a cylinder in said fitting in open communication with water flowing through said fitting, there being a slot in the wall of said cylinder; a removable lining for said cylinder having a slot registering with said cylinder slot; a piston in said

cylinder; two rigidly connected pulleys; a flexible element wound upon one of said pulleys and operatively connected with said piston; and a flexible element oppositely wound on the other pulley and operatively connected with said damper, substantially as described.

5 5. The combination with a boiler-furnace smoke stack damper, of a fitting in the boiler feed pipe; a vertically arranged cylinder in said fitting, said cylinder being open at the bottom to permit entry of water thereto from one side of said fitting and provided with a vertical slot to permit escape of water through the other side of said fitting; a piston in said cylinder; and an operative connection between said piston and damper, substantially as described.

10 6. The combination with a boiler-furnace smoke stack damper, of a fitting in the boiler feed pipe; a vertically arranged cylinder in said fitting, said cylinder being open at the bottom to permit entry of water thereto from one side of said fitting and provided with a vertical slot to permit escape of water through the other side of said fitting; a piston in said cylinder; two rigidly connected pulleys; a flexible element wound upon one of said pulleys and operatively connected with said piston; and a flexible element oppositely wound on the other pulley and operatively connected with said damper, substantially as described.

15 7. The combination with a boiler-furnace smoke stack damper, of a fitting in the boiler feed pipe; a vertically arranged cylinder in said fitting, said cylinder being open at the bottom to permit entry of water thereto from one side of said fitting and provided with a vertical slot to permit escape of water through the other side of said fitting; a piston in said cylinder; a piston rod for said piston operating through the top of said fitting; a weight on said piston rod; two rigidly connected pulleys; a flexible element wound upon one of said pulleys and operatively connected with said piston rod; and a flexible element oppositely wound on the other pulley and operatively connected with said damper, substantially as described.

20 8. The combination with a boiler-furnace smoke stack damper, of a fitting in the boiler feed pipe; a vertically arranged cylinder in said fitting, said cylinder being open at the bottom to permit entry of water thereto from one side of said fitting and provided with a vertical slot to permit escape of water through the other side of said fitting; a piston in said cylinder; a piston rod for said piston operating through the top of said fitting; a weight on said piston rod; two rigidly connected pulleys; a flexible element wound upon one of said pulleys and operatively connected with said piston

rod; a flexible element oppositely wound on the other pulley and operatively connected with said damper; and a dash pot arranged to check downward movements of said pis-

5 ton rod, substantially as described.

9. A cylinder for an automatic control for boiler-furnaces provided with means at one end for permitting entry of water thereto and a longitudinal slot for permitting es-

10 cape of water therefrom; and a removable

lining for said cylinder slotted to correspond, substantially as described.

In testimony whereof I have signed my name to this specification in the presence of two subscribing witnesses.
